UNITED STATES PATENT OFFICE.

JAMES ARKELL, OF CANAJOHARIE, NEW YORK.

MACHINE FOR MAKING PAPER BAGS.

SPECIFICATION forming part of Letters Patent No. 425,197, dated April 8, 1890.

Application filed April 3, 1888. Serial No. 269,436. (No model.)

To all whom it may concern:

Be it known that I, JAMES ARKELL, a citizen of the United States, residing at Canajoharie, in the county of Montgomery and State 5 of New York, have invented certain new and useful Improvements in Machines for Making Bags, of which the following is a specification.

My invention relates to machines for making bags; and it consists of the devices and 10 elements and combinations of devices or elements hereinafter described, and specifically set forth in the claim.

My present invention relates to that type or 15 class of paper-bag machines which is adapted to the manufacture of satchel-bottom bags, an example of which kind of machine may be seen in United States Letters Patent granted to me December 26, 1871, No. 122,099, and re- 20 issued July 29, 1879; and my invention consists in the novel device or contrivance for insuring and effecting the lifting upwardly and partially folding over of the first-turned flap, which has to be folded over and pasted down in forming the satchel-like bottom of the bag.

25 In the course of my practical and extensive experience with paper-bag machines of that type shown and described in my said Letters Patent above referred to I have found that it was practically impossible to successfully run 30 such machine as fast as it might otherwise be operated, on account of the practical difficulty in moving or operating the lifting and folding blades or folder device used in such a machine for the purpose of gathering up from 35 the face of the revolving cylinder and folding over that portion of the bag-blank which constitutes the first-folded flap manipulated by such pasting and folding machine. These folder blades or devices as heretofore made 40 and as shown and described in my said Letters Patent move upon pivotal points which travel with the revolving cylinder of the machine. The operative ends of the folders swing in the arc of the circle and in a plane 45 approximately parallel with the face of the cylinder. They have therefore at each folding operation to each make a back and forth stroke or vibration; and, having thus to be vibrated in first one direction and then another, I have 50 found it to be practically impossible to increase the speed of the machine to what it might otherwise be run at without causing

frequent derangement and rapid destruction of the working parts of the mechanism by which the said folders are thus thrown alternately and rapidly back and forth to perform the function for which they are employed. By my present invention or improvement I have dispensed with such folder-blades for turning the first-folded flap of the satchel- 55 bottom and have substituted therefor a device which is capable of such rapid operation that the machine may be run at a much greater speed without danger of any derangement of any of its parts, and consequently can be 60 made to turn out a greater number of bags in a given time than it was possible to make in the same time on such machine as was heretofore constructed.

In order that those skilled in the art may 65 make and use my improvement, I will now proceed to describe the same by reference to the accompanying drawings, which form part of this specification, and in which I have shown my invention carried out in that precise form 70 in which I have so far successfully practiced it, and applied to a machine substantially like that made the subject of my patent hereinbefore referred to.

In the drawings, Figure 1 is a side elevation of my improved machine. Fig. 2 is a front view of the same. Fig. 3 is a top view with the pasting-wheel and hopper removed to expose to view the parts and devices below, and illustrating paper bags in process of completion and in the proper position on the cylinder of the machine preparatory to being carried to the pasting and folding mechanisms. Fig. 4 is a partial elevation, on a large scale, illustrating the turning of the folded 85 flaps, &c., according to my present improvement.

In the several figures the same part will be 90 found always designated by the same letter of reference.

In the drawings, A is the frame-work of the machine.

B is the revolving cylinder, on the periphery of which travel the bag-blanks which are to be pasted and folded at one end to complete 95 the satchel-bottom thereof.

C is the pasting-wheel, which runs with its face to and from the pasting-receptacle D, as indicated by the arrow in Fig. 1.

E E are the registering-fingers, formed with arms E', which are vibrated vertically on shaft E² by means of the crank-arm e, pitman e', and cam e² on the shaft of cylinder B.

5 F are the revolving creaser-blades.

G is the fold-pressing device, which is mounted on shaft g and revolved by the band-wheels G' G' in the direction indicated. As shown, the cylinder B has secured on its periphery a series of sectional strips a a and a' a', which are arranged at short distances apart, and which are made to project from the surface of the cylinder, as shown, these strips in the aggregate forming the bed or surface 10 on which the bag-blank rests while being carried around by the cylinder, and while subjected to the pasting and folding operations.

H H are the elastic fingers, by means of which and the usual tapes or bands the bag-blanks fed into the machine are gripped and properly carried along with the cylinder, all of which parts, both as to their construction and mode of operation, are old and substantially like what is shown and described in 15 my said Letters Patent.

K are the novel devices employed according to my present invention for insuring and effecting the lifting up and partially turning over of the first-folded flap, which is made by the machine in forming or completing the satchel-like bottom of the bag. This finger is shown secured to the end of the arm k, which is fixed to the free end of the lever K' and is about opposite to a line at the middle 20 lengthwise of the face of the cylinder B. This lever is pivoted at K' to the frame of the machine, or to a piece secured thereto, and has given to it a tension by means of the spring k², which tension operates to throw the said 25 lever in a direction opposite that indicated by the arrow in the drawings.

L is a cam secured to the shaft f of the revolving creaser-blades F, so as to revolve with the same. This cam, as it is revolved in the direction indicated by the arrow, operates at 30 stated times against the upper end of the lever K', or against a friction-roller l, pivoted in the said lever, as shown in Fig. 1, to throw the long arms of said lever outwardly in the direction indicated by arrow and hold it in 35 that situation for a short time and until the cam has been revolved so as to bring its flap and straight line of surface opposite said friction-roller, when the tension-spring k² will 40 impart a quick movement to said arm, so as to cause the fold lifting and turning finger to almost touch the middle strip a', and thus 45 come into contact with the paper resting on that strip.

50 It is to be understood that for the purpose of turning down or folding over the last-formed flap of the satchel-bottom precisely the same devices are employed as are shown and described for that purpose in the drawings and specification of my said reissued 55 patent, heretofore referred to.

The general operation of my improved ma-

chine may be thus briefly explained. The drawings at Figs. 3 and 6 show the bottom end portion of an uncompleted paper bag 70 which is being carried by the cylinder B and its adjuncts to the folding mechanisms to be operated upon, thereby to effect the turning and folding of the bottom flaps m and n, respectively, into place on the "top portion," so 75 to speak, of the bottom of the bag. As the cylinder B revolves with the elastic fingers H and endless bands I, firmly holding the bag-blanks P, the latter would be carried progressively forward and beneath the pasting-wheel with the section or fold m leading and the flap-section n following, as shown by full lines in Figs. 3 and 6, and is then carried toward and opposite to the pair of creasing-blades F and the improved novel turning device K. When in this forward movement of the bag-blank P the free end edge of its fold m is about at the point v, Fig. 4, the cam L will be moved to such a position that it will be out of pressing-contact with the friction-wheel l or lever K, and the instant this pressure of said cam on said lever ceases the tension-spring k² will operate to move the finger K with great rapidity toward the cylinder and into a position in front of the leading end 90 of the said section-fold m, and will there remain until the action of the cam L on lever K' will throw said lever and the finger K back to its normal position, as shown by full lines in Fig. 4, and as the progressive movement 100 of the bag-blank P is continued past the finger K, while the latter is in the position indicated by a dotted line, as at Fig. 4, the forward movement of the fold-section m will be momentarily checked by the presence of the 105 finger K, although the body portion of the bag-blank P will continue to move along, so that the fold-section m will be forced to turn or bend over at crease-line r and toward the body portion of the bottom of the bag, as indicated by the dotted line m' at Fig. 4, and at about the time when this fold m is being turned to the position indicated by the dotted line m' the partially-folded-over flap will 110 pass into the bite of the pressure device G, 115 which will effect a final depression and pasting down of the bottom fold m. The rotation of the cylinder continuing, the bag-blank P, with its completely-folded-down bottom sections m and n, will be delivered from between 120 the bands I and the strips which form the bed or working surface of the cylinder B.

125 It will be understood that in carrying my invention into operation mere modifications and variations in the details of construction of the mechanism shown may be made without departing from the spirit of my improvement, and that either one or more of such folding-over fingers as I have shown at K may be used, according to the size of the bag and 130 its fold and the degree of stiffness of the paper of which the bag may be manufactured.

Having now so fully explained the nature of my invention that those skilled in the art

can make and use my improvement, what I claim as new, and desire to secure by Letters Patent, is—

In a machine of the type shown and described for pasting and folding down the bottom flaps of a satchel-bottom bag, the combination, with the cylinder on the face of which the bag-blank travels and has its bottom portions pasted and folded, of a detaining and turning finger operating to approach the periphery of the cylinder in a plane trans-

verse to the axis of the latter and to recede from the cylinder in the same plane or path of motion after having partially turned over the flap to be folded, all in substantially the 15 manner and for the purposes hereinbefore set forth.

JAMES ARKELL.
